UNITED STATES PATENT OFFICE.

FELIX KOHN, OF VIENNA, AUSTRIA-HUNGARY.

METHOD OF MANUFACTURING TARSIA-WORK.

943,309.

Specification of Letters Patent. Patented Dec. 14, 1909.

Application filed September 3, 1908. Serial No. 451,545.

To all whom it may concern:

Be it known that I, FELIX KOHN, fabri-
-cant, a subject of the Emperor of Austria-
Hungary, and a resident of Vienna, in the
5 Empire of Austria-Hungary, I., Elisabeth-
strasse 24, have invented a Method of Manu-
facturing Tarsia-Work; and I do hereby de-
clare the following to be a full, clear, and
exact description of the invention, such as
10 will enable others skilled in the art to which
it appertains to make and use the same.

The subject-matter of the present invention
is an improved method of manufacturing
tarsia-work by stamping out inlays and
15 pressing the same into the bed-plate.

A method is already known according to
which metallic inlays in wood are made by
the inlays being stamped out by means of a
20 top and bottom stamp, whereupon the con-
cerned cuts or incisions are made in the bed-
plate by means of the same cut, and lastly the
inlays are pressed into these incisions. In con-
tradicition to this known method, the
25 present invention consists substantially in
the material which is to be inlaid being
pressed by means of a puncheon through the
matrix into the object which is to be inlaid
placed against the matrix, so that the pro-
30 cess of inlaying can be performed in one
operation. For this purpose an apparatus
such as is shown in the accompanying drawings
may be employed.

In the drawings:—Figure 1 is a vertical
35 longitudinal section through the device in
the position immediately before pressure is
applied; Fig. 2 is a similar view of the de-
vice in the position in which the inlay ma-
terial has been stamped out and not pressed
40 into the object to be inlaid; Fig. 3 is a like
view of the device when in the final position;
Fig. 4 is a plan view of the matrix; Figs. 5,
6 and 7 are detailed views, on a larger scale,
of the parts with the same relative positions
45 as in Figs. 1, 2 and 3.

Referring to the drawing, the apparatus
45 consists of a puncheon plate 1 having on its
lower side a die portion 2, of the configura-
tion of the inlay which is to be applied.

50 3 is a matrix having a portion cut away
to correspond in shape to that of the die.
The matrix is of a thickness somewhat less
than the height of the die portion 2 of the
puncheon for the reasons stated hereafter.

The operation is as follows:—The object

which is to be inlaid, for example a flat piece 55
of wood 7, is placed on a support 6; then the
matrix 3 is put on the piece 7, and a sheet of
inlay 9, for example a sheet of veneer, is
placed on the matrix. The puncheon 1 with
its die portion 2 is then arranged over the 60
veneer, and in order to enable it to coöperate
properly with the matrix 3, pegs 10 are pro-
vided on the puncheon which fit into corre-
sponding holes in the matrix and thereby
guide the latter. The die is then forced 65
downwardly and, on account of the coöpera-
tion of the die portion 2 with the matrix 3,
the inlay material 9 will have a portion 11
stamped out in the corresponding shape, and,
as the pressure is continued, the stamped out 70
inlay material will finally be stamped into
the article to be inlaid, as shown in Figs. 3
and 7. As the stamped out material is guided
in the matrix 3 it cannot deviate laterally
and an accurate inlay is effected. 75

The height of the die portion 2 of the
puncheon is greater by the thickness of the
inlay material 9 than the thickness of the
matrix 3 and therefore the inlay material is
pressed into the article to be inlaid exactly 80
the thickness of the inlay material, so that a
finished inlaid plate with the surface of the
inlay flush with the surface of the base is
produced.

What I claim as my invention and desire 85
to secure by Letters Patent is:

1. The method of manufacturing tarsia
work, which consists in punching at one op-
eration the inlay from a sheet of material
through a properly shaped matrix or die, 90
while the die is in contact with the object to
be inlaid, into the object to be inlaid.

2. The method of manufacturing tarsia
work, which consists in punching at one op-
eration the inlay from a sheet of material 95
through a properly shaped matrix or die,
while the die is in contact with the object to
be inlaid, into the object to be inlaid until
the upper surface of the inlay is flush with
the object. 100

In testimony whereof I have signed my
name to this specification in the presence of
two subscribing witnesses.

FELIX KOHN,
